FOLDABLE SUPPORT

Arthur J. Bradford, Wilmette, Ill., assignor to
Technical Service Inc., Detroit, Mich., a corporation of Michigan

Application July 25, 1945, Serial No. 607,015

8 Claims. (Cl. 248—166)

1

This invention relates to supports and in particular to foldable or collapsible supports.

One object of this invention is to provide a foldable support having legs which are automatically spread apart as they are swung downwardly to their open positions.

Another object is to provide a foldable support having legs which may be folded from divergent extended positions to approximately parallel folded positions, with means for automatically spreading the legs apart as these are swung outwardly from their closed to their open positions.

Another object is to provide a foldable support having pairs of legs disposed at opposite ends thereof and foldable from nesting positions outwardly and automatically to extended divergent positions.

In the drawings:

Fig. 1 is a side elevation of a preferred embodiment of the foldable support of this invention.

Fig. 2 is an end elevation of the foldable support shown in Fig. 1.

Fig. 3 is a horizontal section along the line 3—3 of Fig. 2.

Fig. 4 is a side elevation of the foldable support with the legs in their folded positions.

Fig. 5 is a bottom plan view of the foldable support of Fig. 4, with the legs in their folded and nesting positions.

Fig. 6 is a perspective view looking upward toward one end of the foldable support of Fig. 1 with the legs in their open and divergent positions.

In general, the foldable support of this invention consists of a base having a pair of legs secured at spaced locations thereon, together with a pair of pivoted connecting links which are in turn connected to a third link secured at its opposite end to the base. The linkage is so constructed and arranged that as the legs are swung outward from their nested positions wherein they lie approximately parallel to one another, they are automatically extended laterally into divergent positions. The support is adapted to a variety of purposes and is especially well adapted for supporting projection screens.

Referring to the drawings in detail, Fig. 1 shows a preferred embodiment of the foldable support as consisting of a base 10 having brackets 11 secured as at 12 to its opposite ends or at spaced locations thereon, the ends of the brackets 11 being bent as at 13, and provided with aligned holes 14. Extending between the opposite holes 14 and secured therein is a pivot shaft 15 upon

2

which is pivoted a carrier 16 having bent side walls 17 similar to the bent portions 13 of the brackets 11. The bent portions 17 are provided with aligned holes 18 through which the pivot shaft 15 passes, the portions 13 and 17 lying adjacent one another. The carrier 16 is provided with an inwardly bent tab 19 the ends of which serve as a stop.

The carrier 16 is provided with spaced apertures 20 for receiving pivot pins 21. The latter pass through bores 22 in legs 23 of channel cross-section. The pivot pins 21 are spaced away from the lower edge 24 of the carrier 16 and also from the edges of the tab 19 so that these act as stops to limit the swinging of the legs 23 around their pivot pins 21.

Pivoted as at 25 and 26 to each adjacent pair of legs 23 are links 27 and 28 which are pivoted together at a common meeting point or pivot pin 29. The link 27 is extended beyond the pivot pin 29 in an extension 30 having a pin 31 which cooperates with a notch 32 in the link 28 to lock the links 27 and 28 together.

The pivot pin 29 also carries a yoke 33 pivotally mounted thereon and carrying a pivot pin 34 upon which one end of a link 35 is pivotally mounted. The other end of the link 35 is pivotally connected to a pivot pin 36 mounted upon the bent bracket 37 which is secured as at 38 to the support 10 at a location spaced away from the bracket 11.

In operation, in their folded position the legs 23 lie adjacent and approximately parallel to one another with the legs 23 from one end of the base 10 lying between the legs 23 from the other end thereof. The links 27 and 28 are in their folded positions, and the operating links 35 lie between the legs 23 approximately along the center line of the support 10.

To unfold the legs 23 and set up the support, the operator merely swings the legs 23 outward from the position of Fig. 4 to that of Fig. 1. As the legs swing outward, the folded links 27 and 28 become extended into a straight-line position (Fig. 6) as the operating link 35 pulls them into this position. As the links 27 and 28 thus become aligned with one another, they push the legs 23 apart, bringing them into the positions shown in Figs. 2 and 6, and the pin 31 enters the notch 32 to lock the parts together.

To fold up the support, the operator merely reverses the foregoing procedure. The links 28 and 27 fold into the positions shown in Figs. 4 and 5 and the operating link 35 automatically draws them and the legs 23 together.

While a specific embodiment of the invention has been described and illustrated, it will be understood that various modifications may be made within the scope of the appended claims without departing from the spirit of the invention.

What I claim is:

1. In a foldable support, a base, a pair of elongated supporting members pivoted to said base on a lateral axis relatively to said base, and additionally pivoted to said base on a longitudinal axis relatively thereto, and means for automatically moving said supporting members laterally away from each other in response to their being swung longitudinally away from said base.

2. In a foldable support, a base, a pair of elongated supporting members pivoted to said base on a lateral axis to said base and additionally pivoted to said base on a longitudinal axis relatively thereto, foldable connecting links disposed between said supporting members remote from said pivot axes, and an operating link pivotally connected near one end to said connecting links and pivotally connected near the other end to said base at a location spaced apart from said pivot axes said operating link being operative to automatically unfold said connecting links to effect lateral divergence of said supporting members in response to a longitudinal swinging of said supporting members relatively to said base.

3. In a foldable support, a base, a carrier pivoted to said base on a lateral axis relatively to said base, a pair of elongated supporting members pivoted to said carrier longitudinally relatively to said base, a pair of foldable links pivoted at their outer ends respectively to said supporting members at locations away from their pivots on said carrier and pivoted to one another at a common pivot near their outer ends, and an operating link pivotally connected at its outer end to said foldable links adjacent said common pivot and pivotally connected at its inner end to said base at a location remote from said previously-mentioned pivots, said operating link being operative to automatically unfold said foldable links in response to the swinging of said supporting members longitudinally relatively to said base.

4. In a foldable support, a base, a carrier pivoted to said base on a lateral axis relatively to said base, a pair of elongated supporting members pivoted to said carrier longitudinally relatively to said base, a pair of foldable links pivoted at their remote ends respectively to said supporting members at locations away from their pivots on said carrier and pivoted to one another at their other ends, and an operating link pivoted near one end to said foldable links in the vicinity of their common pivot and pivoted near the other end to said base remote from the pivot axes of said elongated supports.

5. In a foldable support, a base, two pairs of elongated supporting members pivoted to said base on lateral axes relatively to said base at spaced locations thereon, and also pivoted to said base on longitudinal axes relatively to said base, a pair of foldable links pivoted at their outer ends respectively to each pair of said supporting members at locations away from their pivots on said base, each pair of foldable links being pivoted to one another at a common pivot near their inner ends, and an operating link pivotally connected

at its outer end to each of said pairs of foldable links adjacent said common pivot, said operating links being pivotally connected at their inner ends to said base at locations remote from said

5 previously-mentioned pivots, said operating links being operative to automatically fold one pair of said supporting members into a position inside of the other pair in response to the swinging of both pairs of said supporting members toward each other into positions coextensive with said base.

6. In a foldable support, a base, two pairs of elongated supporting members pivoted to said base on lateral axes relatively to said base at spaced locations thereon, also pivoted to said

15 base on longitudinal axes relatively to said base, one pair of said supporting members being foldable into a position inside of the other pair when both pairs are folded toward each other into positions coextensive with said base, and means responsive to a swinging of said supporting members from said folded positions toward positions transverse to said base for automatically effecting lateral divergence of said supporting members.

7. In a foldable support, a base, a pair of carriers pivoted to said base on lateral axes relatively thereto at spaced locations thereon, a pair of elongated supporting members pivoted to each carrier on longitudinal axes relatively to said base, a pair of foldable links pivoted at their outer ends

30 respectively to each pair of said supporting members at locations away from their pivots on said carrier, each pair of foldable links being pivoted to one another at a common pivot near their inner ends, and an operating link pivotally connected

35 at its outer end to each of said pairs of foldable links adjacent said common pivot, said operating links being pivotally connected at their inner ends to said base at locations remote from said previously-mentioned pivots, said operating links

40 being operative to automatically fold one pair of

45 said supporting members into a position between the other pair in response to the swinging of both pairs of said supporting members toward each other into positions coextensive with said base.

8. In a foldable support, a base, a pair of carriers pivoted to said base on lateral axes relatively thereto at spaced locations thereon, a pair of elongated supporting members pivoted to each carrier on longitudinal axes relatively to said base,

50 one pair of said supporting members being foldable into a position between the other pair when both pairs are swung toward each other into positions coextensive with said base, and means responsive to a swinging of said supporting members from said folded positions toward positions transverse to said base for automatically effecting lateral divergence of said supporting members.
